UNITED STATES PATENT OFFICE

157,947

RECEPTACLE FOR TOOTHBRUSHES OR
THE LIKE

Lewis Egerman, Yonkers, N. Y.

Application August 31, 1948, Serial No. 148,386

Term of patent 3½ years

(Cl. D4—3)

To all whom it may concern:

Be it known that I, Lewis Egerman, a citizen of the United States of America, residing in Yonkers, county of Westchester, and State of New York, have invented a new, original, and ornamental Design for a Receptacle for Toothbrushes or the like, of which the following is a specification, reference being had to the accompanying drawing, forming part thereof, wherein.

Figure 1 is a front perspective view of a receptacle for toothbrushes, showing my new design.

Figure 2 is a rear elevational view on a smaller scale.

Figure 3 is an end elevational view of Figure 2, and

Figure 4 is a bottom plan view thereof.

I claim:

The ornamental design for a receptacle for toothbrushes or the like, substantially as shown.

LEWIS EGERMAN.
